UNITED STATES PATENT OFFICE.

BRATHER U. ANNAS, OF SAWMILL, NORTH CAROLINA.

RAILWAY-JOINT.

No. 877,694.

Specification of Letters Patent.

Patented Jan. 28, 1908.

Application filed July 11, 1907. Serial No. 383,208.

To all whom it may concern:

Be it known that I, BRATHER U. ANNAS, a citizen of the United States, residing at Sawmill, in the county of Caldwell, State of North Carolina, have invented certain new and useful Improvements in Railway-Joints; and I do hereby declare the following to be a full, clear, and exact description of the invention, such as will enable others skilled in the art to which it appertains to make and use the same.

This invention relates to new and useful improvements in railway joints and it has more particular reference to a joint formed as a chair and adapted to coöperate with one or more fish plates, the use of the latter being optional.

The invention especially resides in the novel construction, combination and arrangement of parts, and it has for its object to provide a railway joint which shall serve to effectually prevent the rails from spreading or from sinking in at their meeting ends.

The details of construction will appear in the course of the following description, in which reference is had to the accompanying drawings forming a part of this specification, like characters of reference designating similar parts throughout the several views, 30 wherein:

Figure 1 is a plan view showing the manner of use of a joint constructed in accordance with the present invention. Fig. 2 is a sectional view on the line 2—2 of Fig. 1. Fig. 3 is a detailed perspective view of the member forming the subject matter of the present invention. Fig. 4 is an elevation looking at the outer side of the joint.

The joint comprehended in the present invention comprises essentially a member designated generally by the numeral 5 and including a body or base portion 6, formed with openings 7 for the passage of spikes or bolts 8 which are employed to fasten said member to the tie 9. The body portion 6 has its blank formed with parallel kerfs and the material between said kerfs is bent upwardly to afford a resilient integral fish plate 10, adapted to bear against the ends of the rails on their inner sides. The kerfs above mentioned also afford extensions 11, which pass beneath the rails 12, and serve as base pieces, the extensions 11 having their extremities inturned to afford lips 13 which

overhang the flanges of the rails 12 and which, in the preferred embodiment of the invention coöperate with a fish plate 14, the latter being held by bolts 15 engaged through the webs of the rails 12 and through the fish plate 10.

The joint is assembled by engaging the lips 13 with the outer flanges of the rails and then by springing the fish plate 10 over the inner flanges. The lips 13 and the fish plate 10 afford a means for holding the rail from spreading as well as for permitting of the fastening of the meeting ends, and the extensions 11 afford a means for preventing the rails 12 from sinking into the tie at the joint.

While it is preferred to use this device at the joint, it is to be understood that the members 5 may be arranged along the body portions of the rails at selected determinate intervals for the purpose of reducing the number of ties ordinarily employed, so that a consequent saving in timber is effected.

The invention is simple in its structural details, inexpensive to manufacture and practical and efficient in use.

From the foregoing description it will be seen that simple and efficient means are provided for accomplishing the objects of the invention, but while the elements herein shown and described are well adapted to serve the functions set forth, it is obvious that various minor changes may be made in the proportions, shape and arrangement of the several parts, without departing from the spirit and scope of the invention as defined in the appended claim.

What is claimed is:

A device of the type set forth, comprising the combination with rail sections and a tie, of a member including a base or body portion formed with parallel slits, the said member being secured to the tie, the material between said slits being bent upwardly to afford a resilient integral fish plate, and the material on each side of said slits being extended and affording base pieces having their extremities inturned as lips as and for the purpose set forth.

In testimony whereof, I affix my signature, in presence of two witnesses.

BRATHER U. ANNAS.

Witnesses:

W. E. STARNES,
R. C. B. MARTIN.
